JOHN GARDNER, OF NEW HAVEN, CONNECTICUT.

Letters Patent No. 72,013, dated December 10, 1867.

IMPROVEMENT IN CAPPING SCREWS.

The Schedule referred to in these Letters Patent and making part of the same.

TO WHOM IT MAY CONCERN:

Be it known that I, JOHN GARDNER, of New Haven, in the county of New Haven, and State of Connecticut, have invented certain new and useful Improvements in Capped Screws; and I hereby declare the following to be a full, clear, and exact description of the same, reference being had to the accompanying drawings, in which—

Figure 1 represents a top view of a cap made in accordance with my invention.

Figure 2 is a vertical section on the line $x y$, fig. 1.

Figure 3 is a like section of a modified form of the cap in the direction of the length of the nick.

Figure 4 is a vertical section of so much of an apparatus for closing the cap upon the head of the screw as is needed to illustrate my invention.

Figure 5 is a vertical section of a round-headed, and

Figure 6 a like section of a flat-headed capped screw, the section in each case being transverse to the nick in the screw-head and cap.

My invention relates to the method of capping screws, by closing upon the head of the screw a metal cap in which a slot has been formed to correspond with the nick in the screw-head.

One important drawback to the successful operation of this and other methods of capping screws has arisen from the difficulty which has been experienced in adjusting the screw and its cap in the closing-die to their proper relations to each other, so that the slot in the cap shall be brought immediately over the nick in the screw, and in order to effect this result mechanisms of more or less complicated structure have been required. And in like manner when a blank cap is closed upon the screw-head, as in some cases has been done in order to find the nick in the screw-head so as to punch the slot in the cap, it becomes necessary to employ apparatus of a peculiar nature to find the nick, and to form the slot with accuracy and without damage to the cap.

The object of my invention is to remedy these difficulties, and to so form the cap that it may be closed upon the screw-head in any ordinary or suitable die without the addition of the mechanisms above mentioned, as heretofore required to hold the cap and screw in their proper relations to each other. To this end, in forming the slot in the cap, I cut out the metal on the sides of the slot only, without disconnecting it at the ends of the slot from the other portion of the cap, and the metal strip thus formed is depressed or forced below the face of the cap, so that when the latter is applied to the screw-head, the metal strip will "line," or be in contact with the bottom of the nick in the said screw-head. In order to thus form the slot in the cap, it can be placed upon a die of suitable form, and then, by the action of a punch or die, the sides of the slot cut out and the metal strip depressed, as above stated. When the nick in the screw-head is of no great depth, as in the case of flat-headed screws, the sides of the slot in the cap need not be cut out, but by the action of a die or punch, as before, the cap may be depressed at the point where the slot is to be formed without cutting, so that when it is applied to the screw-head, the sides, as well as the bottom of the nick in the latter, will be lined by the cap, which will thus cover and extend continuously over every portion of the screw-head.

Among the many advantages which result from my improved method of forming the slot or depression in the cap, there are two of special importance:

First, the metal strip, or depression formed in the cap, serves to centre or to assure the screw and cap in their proper relations to each other during the operation of capping the screw. When the cap and screw are placed together in the closing-die, the portion of the cap which is depressed fits in the nick in the screw-head, and thus holds the screw and cap in position until the latter, by the action of the die, is closed firmly upon the screw-head.

Second, in using ordinary capped screws, in which the metal is entirely cut away at the point where the slot is formed, it often happens that the screw-driver slips from the nick, and, catching against the metal cap, causes it to turn so as to throw the slot out of line with the nick. But under my invention the depressed metal of the cap which lines the bottom or bottom and sides of the nick in the screw-head, being connected with and forming part of the cap, prevents the latter from turning, and holds the slot in the same to its place over the nick in the screw.

There are also other advantages incident to this method of lining the nick in the screw-head, as, for instance,

a more ornamental appearance is given the screw, and the nick in the same protected from rust and consequent damage.

In order that the nature of my invention may be the better understood, I will now proceed to a more detailed description of the manner in which the same is or may be carried into effect, by reference to the drawings accompanying and forming part of this specification. The cap A, which is made of brass or other suitable metal, after being struck up in the usual manner into the required form, is placed upon a die, where, by the action of a punch of suitable form, the slot a is formed. The metal is cut away on the sides b of the slot only, and not at the ends c, where it still remains connected with the cap. The metal strip d, thus formed, is by the action of the punch depressed below the surface of the cap to a distance corresponding to the depth of the nick in the screw-head to which the cap is to be applied, as seen in fig. 3.

Instead of first striking up the cap into shape, and then forming the slot, the two operations may, if desired, be performed simultaneously in a die of suitable construction. In case the cap is formed, as shown in figs. 1 and 2, to fit a round-headed screw, it is preferable, owing to the depth of the nick in such screws, to cut away the metal on the sides of the slot, as represented. But when the cap is shaped to fit a flat-headed screw, as seen in fig. 3, the metal at the point where the slot is usually formed, instead of being cut away, as shown in the drawings, may be simply struck up or depressed so as to fit the nick in the screw-head, the cap in such case being composed of a continuous and unbroken piece of metal. The cap in which the slot is thus formed, is, together with the screw to be capped, placed in any ordinary or suitable screw-capping apparatus, and by the action of this the cap is then closed tightly upon the screw-head. The strip or depressed portion d of the cap fits in the nick in the screw-head, and serves to hold the slotted cap in proper position upon the said head during the process of the operation.

In fig. 4 is represented, in illustration of my invention, one method of closing the cap. The closing-die is composed of the two parts B C, the former, which is stationary and attached to the bed of the machine, being intended to receive the cap and head of the screw, the latter constituting the movable portion of the apparatus, which, when pressed upon the bed B, will close the cap upon the screw. The cap A is first placed in an inverted position in the matrix or form h of the bed B, and the head of the screw is then placed in the cap, being turned until the metal strip d of the cap fits in the nick, as seen in the figure referred to. When the two are thus fitted together, it will be seen that no matter to what extent the screw may be turned in the die, the strip d, which is held in the nick of the screw, will cause the cap to follow such movement; thus maintaining at all times the slot in the cap in its proper relations to the nick in the screw-head. The die C, in its descent, closes that portion of the cap which extends above the screw-head, upon the head, and thus unites the two firmly together, as seen in figs. 5 and 6, the former representing a round-headed screw capped and finished, and the latter being a like representation of a flat-headed screw.

Having now described my invention, and the manner in which the same is or may be carried into effect, what I claim, and desire to secure by Letters Patent, is—

1. In the method of capping screws, I claim cutting away or depressing the cap at the point where it meets the nick in the screw-head, substantially as described, so that such cut away or depressed portion, while connected with and forming part of the cap, shall lie within or "line" the nick in the screw-head, as set forth.
2. A capped screw in which the slot or depression in the cap corresponding to the nick in the screw-head is formed, substantially in the manner and for the purposes herein shown and described.

In testimony whereof, I have signed my name to this specification before two subscribing witnesses.

JOHN GARDNER.
